[57] CLAIM

The ornamental design for a compact low profile communication analyzer for receiving insertable smart modules, as shown and described.

DESCRIPTION

FIG. 1 is a top, right, and front perspective view showing our new design for a compact, low profile communication analyzer for receiving insertable smart modules shown in full line;

FIG. 2 is a left side elevation view thereof;

FIG. 3 is a rear elevation view thereof; and,

FIG. 4 is a bottom plan view.
